ABSTRACT: A gaming device including a gaming table having a flat surface with raised sides and depressed pockets, a plurality of flat circular discs, and cue sticks to be used to propel one disc against another in order to place a disc in a depressed pocket. The gaming table is supported by a swivel that allows said table to be rotated by the player. The disc may have an upper surface with a central truncated cone configuration so that the cue stick may be used to propel the disc when disposed thereagainst.

PATENTED DEC 15 1970

ATTORNEY

GAME COMBINED CUE AND DISC

BACKGROUND OF THE INVENTION

This invention relates to a new and improved gaming device, and, more particularly, to a gaming device including a rotatable gaming table having a flat surface with raised sides and depressed pockets, flat circular discs, and cue sticks to be used to propel said discs against one another and into the pockets.

In the past, various games have been devised utilizing a table having a flat felt deck with raised sides and depressed pockets, balls on the deck, and cue sticks to propel the balls. The game is played by moving the balls about the deck into the pockets. Other games, such as, a scuffle board utilize cue sticks to propel discs on a flat surface.

SUMMARY OF THE INVENTION

The present invention relates to a new and improved gaming device including a gaming table having a flat surface with raised sides and depressed pockets, circular discs having a flat base, and tapered sticks used to propel one disc against another in order to deposit a disc in the depressed pockets. The gaming table is supported by a swivel in order to allow the table to be rotated in relation to a player.

It is an object of this invention to provide a new and improved gaming device.

It is another object of this invention to provide a gaming device that may be rotated in relation to a player who may remain stationary.

A further object of this invention is to provide a gaming device including a table having a hard flat surface, and plurality of discs that can withstand hard use by children and the harsh weather conditions.

An additional object of this invention is to provide a gaming device having a rotatable table that enables the player to use a long cue stick to propel a disc from any position on the table even though the table is placed in a relatively small room.

In accordance with these and other objects which will be apparent hereinafter, the instant invention will now be described with particular reference to the accompanying drawing.

BRIEF DESCRIPTION OF THE DRAWING

In the drawing:

FIG. 1, is a top view of the gaming table;

FIG. 2, is a cross-sectional view of FIG. 1, taken along the lines A-A and looking in the direction of the arrows;

FIG. 3, is a cross-sectional view of one embodiment of a disc; and

FIG. 4, is a cross-sectional view of another embodiment of a disc.

DESCRIPTION OF THE PREFERRED EMBODIMENT

Referring now in detail to the drawing, wherein an embodiment of the invention is shown, and referring, particularly, to FIG. 1, the gaming table, generally designated by numeral 2, has a flat playing surface 4 with raised sides 6, 10, 14 and 18, and depressed pockets 8, 12, 16 and 20 at each junction of the raised sides. Plastic, fiber glass, or wood may be used in the manufacture of the gaming table 2. A fiber glass table will withstand rough use as well as varying weather conditions.

The table is connected to a swivel 22, shown in FIG. 2. The

swivel 22 includes a plate 24 attached to the table 2 and a plate 26 that may be connected to ordinary table legs or collapsible legs (not shown). The plate 26 may be used as a base to support table 2 on another surface, such as, another table or a floor. Any well known swivel means 28 may be utilized to provide means that will allow the table 2 to rotate in relation to stationary plate 26.

Referring now to FIGS. 1, 3 and 4, the gaming device also includes a plurality of discs 30 and a cue disc 32. The discs 30 may have numbers painted or engraved on the top of each disc. The cue disc 32 may be larger than the other discs 30 as shown in FIG. 1. Cue discs 32, shown in FIGS. 1 and 3, has a rounded upper edge to allow a cue stick 34 to propel the disc away from a position adjacent to a raised side of the table. Cue disc 36, shown in FIG. 4, has a depression in the form of a ring in the top of the discs. The sides are slanted, as shown, in order to allow a player to hit the discs with a cue stick 34 when the disc lies against one of the raised sides of the table 2.

It should be noted that table 2 may have a circular configuration with the depressed pockets around the edge or with a depressed pocket in the middle of the table.

In use, the circle 38, drawn on the table 2, may be used as a starting circle. The cue stick 34 is used to strike the cue disc, to propel it against the other discs 30. The discs 30 are propelled in the direction of the depressed pockets. The object of one game played on this gaming device is to place all the discs 30 in the depressed pockets.

When table 2 is placed in a small room, where the wall may interfere with the proper use of the cue stick, the table may be rotated about on the swivel 22 relative to the position of the player, so that the cue stick may be moved in a horizontal position without contacting the walls of the room.

The instant invention has been shown and described herein in what is considered to be the most practical and preferred embodiment. It is recognized, however, that departures may be made therefrom within the scope of the invention. Therefore, the instant invention is not to be limited to the details discussed herein but to be accorded the full scope of the claims so as to embrace any and all equivalent apparatus and articles.

I claim:

1. A gaming device comprising:
a gaming table including;
a flat playing surface;
raised side surfaces;
depressed pockets in each corner of said playing surface
with the adjacent raised side surfaces meeting at a ninety
degree angle behind the depressed pocket;
a swivel device connected beneath said flat playing surface
to allow said flat playing surface to rotate about the swivel
device;
means connected to said swivel device for supporting said
swivel device above a floor surface, a cue stick; and
a plurality of discs to be propelled across said flat playing
surface into the depressed pockets, said discs having a flat
bottom surface and an upper top surface with the top sur-
face of at least one of said discs including a central truncated
cone configuration, said truncated cone having
sides providing a contact surface for said cue stick to
propel said discs across said flat playing surface into con-
tact with the other discs.
